UNITED STATES PATENT OFFICE.

JOHN SCANLAN, OF CHICAGO, ILLINOIS.

TAILOR'S MEASURING DEVICE.

SPECIFICATION forming part of Letters Patent No. 233,441, dated October 19, 1880.

Application filed January 7, 1880.

To all whom it may concern:

Be it known that I, JOHN SCANLAN, of Chicago, in the county of Cook and State of Illinois, have invented certain new and useful 5 Improvements in a Tailor's Measuring Device; and I do hereby declare that the following is a full, clear, and exact description of the invention, which will enable others skilled in the art to which it appertains to construct and 10 make use of the same, reference being had to the accompanying drawings, and to letters of reference marked thereon, which form a part of this specification.

The object of this invention is the improved 15 construction and arrangement of a simple and convenient device adapted to take the accurate measure of any part of the human form.

The nature of this improvement consists in the employment of a series of flexible metallic 20 strips, which are attached to a main or central part composed of the same material. These elastic strips are capable of being adjusted to any required position or angle, and are securely held in the different positions by means 25 of suitable clamping devices, the exact arrangement and operation of which will be hereinafter more fully explained in detail.

To better illustrate my invention, I refer to the accompanying drawings, in which—

30 Figure 1 represents the outlines of the front part of a coat, to which my improved measuring apparatus is attached by means of the belts or bands A A, which are buckled tight around the form to be measured.

35 B represents the larger or main metal strip, to which the smaller series of strips a a are attached. The part B is provided with the slot b, which extends through the longitudinal center of the same, whereby the parts a a may 40 be moved up or down, as occasion requires.

When in use the main part B is made to assume a perpendicular position, and the parts a a made to extend in any direction or angle required in taking the measurement of the 45 different parts of the garment.

C represents sliding boxes on the main part B, which cover the under side and extend over and onto and are turned down on the front or upper side of the part B in the manner shown 50 in the drawings.

Attached to the boxes C, and projecting outward through the oblong slot b, are screw-points a' a', which are adapted to engage with the screw-caps c c, which arrangement adapts the several parts to be clamped in any position 55 to which they are capable of being adjusted. The screw-caps c c, having milled edges, are conveniently operated by the thumb and finger.

a² a² are a series of set-screws having large 60 heads, and are inserted in the boxes a³, which are placed upon the parts or strips a a, and are capable of a longitudinal adjustment, and are securely clamped in the required position by the set-screws a² a². 65

The boxes a³ are provided with the sharp 70 projecting points c', as shown in the sectional detail, Fig. 4, of the drawings. These points are for the purpose of transferring the outlines of the measurement taken to the paper or material from which the pattern is to be cut.

The flexible strip attached near to the upper 75 end of the part B is intended to be used on either side of the same, taking the measurement of the shoulder or neck.

The aperture D at the upper end of the part B is for the reception of a convenient device for attaching the same to the wearing-apparel while the measure is being taken.

d d are hinged joints in the part B, which 80 permit of the same being compactly folded when not in use, the series of smaller strips being folded parallel with the main part.

Fig. 2 represents the apparatus adjusted to 85 take the measure for pantaloons. Fig. 3 is an enlarged representation of a portion of the main strip B, already described in Fig. 1 of the drawings. Fig. 4 represents a transverse section, in detail, taken on the line x x, Fig. 3. Fig. 5 represents a modification in the manner 90 of constructing the device, dispensing with the set-screws a² a² and admitting of the small strips or parts being shortened or lengthened, as required in practical use, and being clamped in position by the screw-caps c c, the marking-points c' being stationary. Fig. 6 represents 95 a longitudinal section taken on the line y y, Fig. 5.

The device shown in Fig. 1 is all that is required in taking the measurement of either 100

the right or left side, both front and back, two perpendicular lines being marked out in the center of the back and breast.

In making use of this measuring device the necessity for first transferring the measurement to paper and cutting out a pattern may be entirely dispensed with, if so preferred, by simply placing the device, after the measure for the garment has been taken, upon the cloth or material from which the garment is to be cut and connecting the outer ends or points by the usual lines.

The series of flexible strips *a a* are capable of being adjusted to any required angle in relation to the main perpendicular part *B*, and are adapted to be moved inward or outward therefrom, thereby shortening or lengthening the same, as may be necessary, the outer ends thereof taking the required points of measurement, which are afterward connected by proper lines, as above stated. By this method and arrangement the employment of the adjustable screw-points *a' a'* may be dispensed with, as may also the use of figures and other characters to indicate the different measurements, thus avoiding a great deal of useless labor, and at the same time obtaining a more accurate measure with less labor and in less time than it is possible to do by any other method.

The series of flexible strips herein shown are not provided with a graduated scale, nor

any lines, figures, or other indicating characters, thus allowing the device to be easily and quickly constructed by any one.

By this simple and convenient device the accurate measure for a garment is quickly taken and any existing deformity is nicely fitted.

This device is equally as well adapted for the use of dress-makers as for tailors.

The apparatus is usually constructed of any material suitable for the purpose, preferably, however, of thin metal, sheet brass or steel.

Having thus described my invention, what I claim, and desire to secure by Letters Patent, is—

In a tailor's measuring device, the method or system hereinbefore described of taking the measure for wearing-apparel, by means of the series of flexible strips *a a*, which are attached at different points to and operated from the main longitudinal part *B*, said strips being adapted to slide outward or inward from the main part *B*, and capable of being adjusted to any required angle relative thereto, substantially in the manner and for the purpose herein set forth.

JOHN SCANLAN.
